UNITED STATES PATENT OFFICE.

JAMES T. THOMPSON, OF CHICAGO, ILLINOIS, ASSIGNEE TO THE THOMPSON AUTOMATIC SIGNAL COMPANY, OF CHICAGO, ILLINOIS, A CORPORATION OF SOUTH DAKOTA.

TRAIN CONTROL AND SIGNAL SYSTEM.

185.527

Specification of Letters Patent. Patented Apr. 13, 1915.

Original application filed January 5, 1912, Serial No. 669,556. Divided and this application filed June 5, 1912. Serial No. 701,744.

To all whom it may concern:

Be it known that I, JAMES T. THOMPSON, a citizen of the United States, and a resident of Chicago, in the county of Cook and State 5 of Illinois, have invented certain new and useful Improvements in Train Control and Signal Systems; and I do hereby declare that the following is a full, clear, and exact description thereof, reference being had 10 to the accompanying drawings, and to the characters of reference marked thereon, which form a part of this specification.

This invention relates to a system of electric signaling or control for railway trains by which to indicate to the engineer, or to arrest or modify the movement of the train, when the train is on an unsafe or prohibited part of the track, and the invention consists in the matters hereinafter set forth and more particularly pointed out in the appended claims.

In the drawings;—Figure 1 is a side elevation, in dotted lines, of a locomotive equipped with my improvements. Fig. 2 is a partial sectional view illustrating the release valve of the train air line pipe controlled by my improved mechanism. Fig. 3 is a view partially in section and partially in elevation of the signaling and controlling apparatus carried by the engine. Fig. 4 is an enlarged horizontal view on the line 4—4 of Fig. 2. Fig. 5 is a diagrammatic view illustrating a track section composed of a plurality of signal blocks equipped with a simple form of signaling system, and illustrating diagrammatically in connection therewith the signal or control device.

As shown in the drawings, 10 designates a release valve of the train line air pipe that is located in a branch 11 of the train pipe 12.

Leading from the valve is a release branch pipe 13 which may be equipped at its outer or upper end with a whistle 14 to give an alarm when air is exhausted through the pipe 13. The branch pipe 13 may be provided, in addition to the whistle with an opening closed by a plug 15. The opening of the whistle is such as to permit the escape of air therethrough to effect a service stop; and when the plug 15 is removed the air escapes from the branch 13 sufficiently rapidly to provide for an emergency stop.

The valve 10 is shown in Fig. 2 and comprises a tapered plug 16 that seats against

an upwardly facing conical seat in the upper end of the pipe 11 that extends into the valve casing 18 and is provided with a guide stem 17 that is guided in said pipe 11. Said valve is normally held against its seat against the pressure of air in the train pipe, so as to seal the pipe 11 by means of a cam arm 19 fixed to a rock shaft 20 mounted in the wall of the valve casing, and to said rock shaft, outside the casing, is fixed a weighted valve actuating arm 22. The weighted arm 22 is normally held in position to lock the valve 10 closed by a latch 25 of general L-shape that is pivoted at 26 in the casing and the shorter arm of which is provided with a tooth 27 that engages a notch 28 in the outer or heel end of the arm 22 so as to hold the valve arm in its uppermost position and the release valve closed. The latch 25 is provided with an elongated, horizontally arranged arm 29 which carries at its free end a transverse armature 30 which contacts with the poles of a two winding electromagnet 32 which, when energized, holds the latch in its raised position to lock the valve actuating arm in its upper position and the valves closed. When the magnet is deenergized the free end of the latch arm 29 drops and releases the latch from the weighted valve actuating arm 22 to permit the valve to automatically open by the action of gravity of said arm 22 and allow air to be released from the valve casing through the pipe 13. The weighted valve arm 22 drops when released by the latch 25 upon a cushion or buffer 35 at the bottom of the casing to relieve the parts of undue shocks or jars.

The arm 22 is adapted to be raised to restore the valve 10 to its normal or closed position, after it has dropped to open the valve, by means of a vertically swinging restoring lever 37 that is pivoted at 38 to one side of the casing A and arranged in a plane at one side of the plane of said arm. Said restoring lever extends outside the casing and is formed at its outer end with a hand piece 39. It is provided at its inner end with a laterally directed lifting member 40 which extends beneath the valve actuating arm, as best shown in Fig. 4, so that when the lever 37 is swung upwardly at its inner end it raises the arm to automatically engage the tooth 27 of the latch 25 with the

actuating arm. Such restoration of the valve actuating arm may take place when the electromagnet 32 is energized so that the arm will be held in its raised position.

5 The restoring lever 37, exterior to the casting A cooperates with a slotted arcuate segment 42, and the lever is adapted to be locked thereto by means of a pin 43, shown best in Fig. 4, extending through registering openings in the segment and lever. The said segment is provided with two sets of openings, one at the upper and one at the lower part thereof, and the pin 43 extends through the upper openings and the lever to lock the lever in its normal position, as shown in Fig. 3. Said pin may be provided with a seal 44 to prevent unauthorized tampering with the lever, and to indicate, by the breaking of the seal, when the lever is operated to restore 10 the train line release valve mechanism. If it be desired to hold the cam actuating arm 22 in its upper position at a time when the electromagnet 32 is not energized, the locking pin 43 may be inserted through the 15 lower holes of the segment 42, and through said restoring lever, to thereby mechanically hold the parts in position to close the valve.

I may provide a counter 45 arranged at the side of the lever, the star wheel 46 of which is adapted to be engaged by a pin 47 which extends laterally from the arm 22 to actuate the counter each time the lever drops downwardly and thereby produce a record of the number of operations of the device.

35 The electromagnet 32 is included in a normally closed circuit, best shown in Fig. 5, which circuit also includes a battery, or other source of energy 33, one side of which battery is connected by the wire 35 to the 40 axles 36 and 37 of the rear drive wheels 38 of the engine and the front wheels 39 of the tender, respectively. The other side of said battery is connected, through the magnet 32, by the wire 40 to one end of the axle 41 of the 45 rear wheels 42 of the locomotive. The ends of the axle 41 are insulated from each other and the axles 36, 37 are insulated from their boxes and the engine and tender frames.

50 When said wheels 38, 39 and 42 are running on electrically continuous rails, or rails that are bonded together, the battery 33 and the magnet 32 are in a circuit which is maintained closed through one of the wheels 42 and the adjacent end of its axle 41, and through one or the other, or both, of the wheels 38, 39 at their axles 37 and 36. The circuit described constitutes a controlling circuit which is movable with the engine or train, and in interruption of said circuit has 55 the effect to deenergize the relay 32 and thereby permit the train control device or a signal associated with said circuit to operate.

In Fig. 5 is shown a section of track embracing two full signal blocks C, D and the far end of the block E, on which latter is

traveling the contact wheels of the controlling circuit of the engine F. The several blocks are equipped with a familiar form of signaling apparatus, in which there is employed at the far end of each block a battery 50, bridged across the track rails which controls a relay magnet 51, bridged across the track rails at the entering end of the block. One of the track rails adjacent to the far end of the block is provided with two relatively short rail sections 53, 54 which are insulated from each other and from the regular track rails, and are sustained by fish plates extending across the two sections. Bond wires 55 extend around said insulated rail sections to maintain electric continuity of the track rails of each block.

56, 56 designate spring terminals which are insulated from each other and are connected to the rail sections 53, 54, and said terminals are adapted to be connected by means of contacts 58 carried by swinging armatures 59 that are acted upon the track relay magnets 51.

The lengths of the rail sections 53, 54 may be such, with respect to the distances apart of the wheels 38, 39 and 42, that when the wheels 38 and 42 are traveling, one on one short rail section and the other on the other short rail section, and the wheel 39 is traveling on the regular track rail in rear of the insulated sections, said latter wheel will reach the rail section 53 before the wheel 38 has passed off the section 54. If it be assumed in Fig. 5 that the contact 58 is closed upon the spring terminals 56, the circuit of magnet 32 and the battery 33 will be closed from one side of the battery 33 through the wire 40, the wheel 42, rail section 53, the spring terminals 56 to rail section 54, and thence through the wheel 38 and axle 37 back to the other side of the battery. When the wheel 38 passes off the insulated rail section 54 the wheel 39 will have passed onto the insulated rail section 53, so that the circuit will, at such time, be closed through the wheel 42, the rail section 54, spring terminals 56, rail section 53 and wheel 39 and its axle 36 back to the battery 33.

In the foregoing description it has been assumed that the circuit is closed at the terminals 56. The said terminals 56, when closed by the contacts 58 and the rail sections 53, 54 connected thereto constitute when the contact wheels 38, 39 and 42 are passing thereover, a loop or partial local circuit through which the controlling circuit is maintained closed, notwithstanding the interruption in the track rail due to the insulation between the rail sections and the regular track rails, so that there will be no break in the controlling circuit, and the train will pass over said insulated rail sections without operating the train control device or signal apparatus. If the loop be 130

open by the separation of the contact 58 and the terminals 56, however, as shown in the block E in Fig. 5, the controlling circuit will be interrupted or opened when the wheels 5, 38, 39 and 42 pass over the insulated rail sections, with the result of deenergizing the magnet 32 and operating the train control device or signal or both.

The said loop or partial local circuit may 10 be opened at the terminals 56 in any convenient manner to effect this result, as for instance, by the throwing of a switch, a semaphore, the opening of a bridge or otherwise short circuiting the track relays 51.

15 This application is a division of my prior application for U. S. Letters Patent, Serial No. 669,556, filed on the 5th day of January, 1912.

I claim as my invention;—

20 1. A signal or control mechanism for railway trains embracing a signal or control device carried by the locomotive, a vertically swinging weighted arm arranged when in its upper position to maintain said device 25 inoperative, and when in its lower position to render the device operative, and having a notch at its heel end, a swinging mechanical latch of general L-shape pivoted at the angle between its arms and having on its 30 shorter arm a tooth to engage the notch of the lever to hold the latter in its upper position and provided at the end of its longer arm, which normally lies horizontally over

the weighted arm, with an armature, an electro-magnet carried by the locomotive 35 and acting on the said armature and said latch to normally hold the arm in its upper position, and electrically actuated means for controlling said electro-magnet.

2. A control mechanism for railway trains 40 embracing, in combination with the air brake train pipe and its release valve, a gravity actuated arm connected to and operating said valve to release air from the pipe, a holding magnet operating to normally hold the arm in position to render the valve inoperative to release air from the pipe, a controlling circuit for said magnet with means to open and close the same, embracing means to automatically open the 45 said circuit to deenergize said magnet and release said arm to open the valve, a lamp circuit embracing a lamp and a battery and two separated contacts, and means on the valve actuating arm to bridge between said 50 contacts to close the lamp circuit when the arm drops to open the valve.

In testimony, that I claim the foregoing as my invention I affix my signature in the presence of two witnesses, this 11th day of 55 May, 1912.

JAMES T. THOMPSON.
